(57) **CLAIM**

The ornamental design for a mirror cabinet, as shown and described.

DESCRIPTION

FIG. 1 is a front perspective view of a mirror cabinet, showing my new design, shown in an open state;
FIG. 2 is a front view thereof;
FIG. 3 is a rear view thereof;
FIG. 4 is a left side view thereof;
FIG. 5 is a right side view thereof;
FIG. 6 is a top view thereof;
FIG. 7 is a bottom view thereof; and,
FIG. 8 is a perspective view showing the mirror cabinet in an alternate closed state.

The broken lines in the drawings illustrate the portions of the mirror cabinet, which form no part of the claimed design.
